United States Patent Office

Des. 182,797

Patented May 20, 1958

182,797

DECK CHAIR FRAME

Robert H. Ensign, Bronxville, N. Y., assignor to Blair Aluminum Furniture Company, Marietta, Ga., a corporation of Georgia

Application September 23, 1957, Serial No. 47,807

Term of patent 14 years

(Cl. D15—11)

FIG. 1

FIG. 2

Fig. 1 is a perspective view of a deck chair frame showing my new design.

Fig. 2 is a side elevation of the deck chair frame shown in Fig. 1.

I claim:

The ornamental design for a deck chair frame, substantially as shown.
